UNITED STATES PATENT OFFICE

2,570,544

GUMMING MACHINE

José Pelaez Guerra, Habana, Cuba

Application December 23, 1946, Serial No. 718,054
In Cuba April 11, 1946

2 Claims. (Cl. 216—20)

1

My invention relates to sewing machines to which certain modifications are made to couple a gumming device, the functioning of which is made to synchronize with that of the machine, thus permitting the gumming of the back or middle of the books, note-books, blocks or copy-books, besides the sewing performed by the machine, to be made in a single operation. This, until now, has been performed separately, resulting in consequent loss of time and money, due to the necessity of employing extra labor as required by the method in vogue.

For a better understanding of the mechanism of the machine in question, I shall refer to the attached drawings, in which identical parts have been described with the same reference numbers.

Figure 1 is an elevated side view of the auxiliary gummed device. Fig. 2 shows the sewing machine in elevated side view with the synchronous mechanism coupled, exhibiting how the gummed strip of the gumming device passes on to the machine. Fig. 3 is a ground plan of the pressure car with its rollers. Fig. 4 gives a side view of the mechanism which is coupled to the sewing machine. Fig. 5 shows a lateral view, contrary to the view given under Fig. 2, of the sewing machine and gumming device coupled to it, showing conspicuously the means of synchronizing the functioning of both. Figure 6 is a front view of the gumming mechanism. Fig. 7 gives a front view of the machine with the gumming mechanism coupled. Fig. 8 is a ground plan of the entire outfit—sewing machine with apparatus for gumming device coupled. Fig. 9 is a view in perspective of the sewing machine as it sews the booklets.

The object of the gumming device is to lay on the gum on one of the surfaces of the strip that has to be adhered to the article that is being sewed in the machine and to continue "feeding" the machine, without effort, with just what it requires. It consists of a tank or recipient shown in the drawings with the number 4, in which the gum is placed. This tank is provided with a support, 12; behind the tank there is a tripod 3 which supports the roll of strip 1, held by the lateral crossarms 2, joined by horizontal axis. One end of the strip is made to pass under a crosspiece 5 arranged on the tank and supported by posts fixed to the sides of it. Said crosspiece sustains a lug, the forward end of which falls upon a guide roller 6 having flanges at its ends, rotatively supported from uprights extending from the sides of the tank, through which the strip passes on its way between another two rollers—an upper roller 7 (also a guide roller)

2

and a lower roller 8, which can be placed on top or at variable distances relative to a cylinder 10 of greater diameter. This adjustment of rollers 7 and 8 being accomplished by means of small levers fixed at one end of the axis and a thumb screw 9. Cylinder 10, rotating upon its axis, is mounted in such manner that the lower portion thereof is submerged in the liquid gum contained in the tank and, upon rotating, carries adhered to its surface a certain quantity of said gum, which may be graduated by adjusting the position of roller 8 with respect to the cylinder. The strip, upon passing under guide roller 7, the lower portion of which remains at a lower level than the upper portion of cylinder 10, is deflected upwards and comes in contact with the cylinder 10, thus acquiring on its lower surface a certain quantity of the gum which said cylinder 10 carries on its exterior surface. The strip then again descends under another auxiliary guide roller 11 supported from the tank sides, and continues outside and beyond the tank towards the mechanism which is coupled to the sewing machine.

The body of sewing machine 26 is provided with its base 25 and wheels with groove or pulleys for receiving the impulse of a motor (not shown) by means of a belt 38 (Figs. 2 and 5).

At the side of the power receiving wheel of the body of the sewing machine, a small pulley 37 is provided for rotation with the power receiving wheel, which by means of belt 46 transmits its rotary movement to a lower pulley 21 with axis 45 that has its support 44 fixed to the table or panel of the machine. Pulley 21 transmits its rotary movement through axis 45 and end pinion 40 to a pinion roller fixed to its axis 18, by means of intermediate pinions 19 and 20, having their axes 39 resting in journal bearings or perforations made in fishplates 43 fixed to the table of the machine.

In front of the roller with fixed pinion 18, there is another roller 17, the position of which relative to the roller with fixed pinion 18 is controlled by a screw 24, the nut 32 of which, is fixed to the table of the machine, and the forward end of said roller pulls in its onward or backward movement, a piece 33 that serves as a support for the axis of roller 17 which, consequently, can be made to approach roller 18 or to recede from it at will, in order to graduate the tension of a continuous felt band 16 that borders externally both rollers and moves while roller 18 is in motion, making roller 17 rotate also upon its axis.

Both rollers 17 and 18 are so positioned that their upper portions extend into openings or

spaces of portions withdrawn from the panel or table of the machine, so that the highest line of their external surface remain upon a level with the upper surface of said panel, and the felt band, 16, upon ascending in roller 18, by virtue of its rotation, passes over the table or panel in the portion comprised between the two rollers, after which it goes down again by the opening corresponding to roller 17.

The strip, already gummed, at its lower surface, on coming out of the gumming device, passes under the panel or table of the machine and, guided by roller or wheel with groove 23 sustained on a fixed support to the table, continues on to the next roller or wheel with groove 22, sustained by support 36, to which it edges and changes the direction of its movement thereby, presenting at the same time the gummed surface upwards. Upon leaving roller 22, it comes in contact with felt 16 upon which it is seated and passes like the latter, over the table at the portion comprised between the rollers 17 and 18. This is the point at which the gummed strip adheres to the note-books, blocks, etc., sewed in the machine.

In fact, the belt band 16 moves in a direction aligned with the sewing piece of the machine, and upon the forward movement of the block or note-book, as the sewing goes on, it situates the stitched part precisely over the gummed surface of the strip, as will be seen in Fig. 8, and continues advancing over the same by the movement of the felt band.

The pressure which the sewed object requires in order that the gummed strip may be sufficiently adhesive, is transmitted to it by a "pressure car," Fig. 3, composed of a set of six rollers, five of which, No. 14, are of greater diameter than that which is situated nearer the sewing machine, indicated by the number 15. The roller 15 only engages the article or booklet and therefore need not exert as great pressure as the other rollers. All of these rollers are situated between the fishplates 39, with their axis resting in openings made in same, said fishplates being united by horizontal crosspieces, two of which carry perpendicularly fixed, two posts or poles which sustain at their upper ends, a rod 43, to which are associated the fore ends of two arms 28 with reinforcing crosspieces 29 and detachable pin 31 which passes through the perforations of the rear ends of arms 28, and the hinges 27 held in position by screws to the panel or table, thus permitting the lifting of the "pressure car."

Two squares 41 and 42, the distances of which from the felt band may vary, are arranged upon the table as guides for the articles to be sewed and gummed, and are provided with screws and nuts, passing through the grooves made in the table.

In Fig. 9 of the drawings, I have illustrated the sewing machine as it sews the booklets 2a, the numeral 1a being used to designate a strip of tarlatan. It will be understood that the tarlatan is gummed in the very middle or ridge of the booklet, for which purpose there is at one end a person who, upon cutting the thread that stitches the booklet, cuts at the same time the strip which gums at the ridge of the same, so as to avoid having to perform this extra labor separately.

From the foregoing explanation, it is seen that

as the sewing progresses, the gummed strip is laid on, covering the seam of the article sewed, automatically and synchronically, one person only being required for cutting the gummed strip when the object sewed comes out from under the "pressure car."

Slight modifications may be made without altering the spirit of the invention, for which reason the patent which I solicit should devolve upon the reach of the following.

I claim:

1. Apparatus for feeding an article and a gummed element past pressure mechanism for causing the gummed element to adhere to the article, said pressure mechanism including a unitary frame rotatably carrying a plurality of pressure rollers arranged in alignment with the direction of travel of the article and gummed element, and the roller at the end of the frame toward which the article and gummed element travel being of reduced diameter relative to the other rollers, and a freely pivoted swinging supporting framework connected to said unitary frame, said swinging framework pivoted on an axis parallel to the direction of travel of the article and gummed element at points laterally disposed relative to said path of travel, said framework having freedom of swinging movement in following the surface contour of the article and gummed element as they pass in contact with the pressure rollers.

2. Apparatus for feeding an article and a gummed element from different positions into juxtaposed position on mechanism for feeding the article and gummed element past pressure mechanism for causing the gummed element to adhere to the article, said pressure mechanism including a unitary frame rotatably carrying a plurality of pressure rollers arranged in alignment with the direction of travel of the article and gummed element, and the roller at the end of the frame toward which the article and gummed element travel being of reduced diameter relative to the other rollers, and positioned so that it contacts only the article, while the remaining rollers contact the article and exert pressure on the article and the gummed element, and a freely pivoted swinging supporting framework connected to said unitary frame, said swinging framework pivoted on an axis parallel to the direction of travel of the article and gummed element at points laterally disposed relative to said path of travel, said framework having freedom of movement in following the surface contour of the article and gummed element as they pass in contact with the pressure rollers.

JOSÉ PELAEZ GUERRA.
